TOOTHPICK DISPENSER

John Edwin Kenkel, Great Falls, Mont.

Application August 29, 1933, Serial No. 687,359

4 Claims. (Cl. 312—75)

This invention relates to dispensing machines and has for an object to provide an improved construction over my prior Patent No. 1,428,439, the object being to provide a construction where-
5 in tooth picks may be vended one at a time in an efficient and desirable manner.

Another object of the present invention is to provide an improved construction wherein nothing is in the way of the fingers when a
10 vended tooth pick is being grasped and removed.

A further object of the invention is to provide an improved simplified structure wherein swinging means are provided which coat with the vended tooth pick and prevent the vending
15 of a second tooth pick until the first tooth pick has been completely removed from the machine.

In the accompanying drawing—

Figure 1 is a longitudinal vertical sectional view through Figure 3 on the line 1—1, dis-
20 closing an embodiment of the invention;

Figure 2 is a view similar to Figure 1 but showing the parts in the position assumed when a tooth pick is about to be removed from the machine;

25 Figure 3 is a sectional view through Figure 1 but approximately on the line 3—3.

Referring to the accompanying drawing by numerals, 1 indicates a housing of any desired kind, which is formed with a chamber 2 in which
30 a supply of tooth picks 3 or other articles to be vended are positioned. The chamber 2 has an inclined bottom 4 arranged at a sufficient pitch whereby the tooth picks will automatically move downwardly under gravity and strike against the
35 swinging abutment 5. Abutment 5 and the extension 6 form an auxiliary bottom having an opening 7.

When the device is operated the abutment 5 moves downwardly until the upper end 8 is
40 substantially flush with the upper surface of the bottom 4, whereby a certain amount of tooth picks may move down and rest on the horizontal support 9, as shown particularly in Figure 2. The device is swung up to the position shown in
45 Figure 2 each time a tooth pick is vended, and consequently one or more tooth picks will be discharged onto the support 9.

As shown in the drawing there is provided a stationary support 10 having spaced notched
50 uprights 11 positioned to receive one or more tooth picks, as shown in Figure 2, when the support 9 is lowered. This support 9 merges into a pointed structure 12 which is positioned as shown in Figure 2 when the parts are lowered,
55 and when it swings again to an upward position

will remove from the notched upright 11 all of the tooth picks, one tooth pick being forced over the abutment 13 and the remaining tooth picks being forced back onto the support 9. The one tooth pick which is forced over the abutment
60 13 will fall onto the arms 14 and move downwardly until it strikes the plate 15. The arms 14 are integral with or rigidly secured to plate 15 and this plate is pivotally mounted at 18 on suitable standards 19, while the slides 17 are
65 pivotally mounted at 29 onto the arms 14. Plate 15 at the upper end is rigidly secured to an arc-shaped shield 21 which with the abutment 5 and associated parts form a constricted or narrow passageway into which the tooth picks move,
70 as shown in Figure 2.

Associated with the arms 14 are plates 17 pivotally mounted at 20 to these arms but otherwise freely movable, whereby as the arms 14 swing on the pin or pivotal support 18, the
75 respective plates 17 will not only move therewith but will, in effect, slide back and forth with the extension 22 beneath the pin 23 which is carried by the standard 10. When the parts are in the position shown in Figure 1 any tooth picks on
80 the arms 14 will slide down to the position shown in Figure 1 where the tooth pick is in contact with the plate 15 and also with the respective plates 17. When the tooth pick is to be removed it is pulled horizontally or on a slight
85 upward curve and the parts will then assume the position shown in Figure 2.

If for any reason a tooth pick should be left in place as shown in Figure 2, the parts will remain in this position with the plates 17 ele-
90 vated. These plates cannot move downwardly and the ejecting projection 12 cannot move upwardly, so that no additional tooth picks will be fed to the dispensing point. However, as soon as the tooth pick is removed the parts will
95 readily fall down to the position shown in Figure 1, and when this occurs the ejecting member 12 will have pushed one tooth pick over the abutment 13 and the remaining tooth picks back on to the support 9. When this occurs the tooth
100 pick ejected will strike the upper surface of the arms 14 and will move downwardly by gravity to the position shown in Figure 1, ready to be removed. When the tooth pick is removed the parts are swung upwardly by the person remov-
105 ing the same until the parts assume the position shown in Figure 2, whereupon the shoulder 24 of the respective plates 17 will be in front of pin 23, so that if a tooth pick is not completely removed this shoulder will prevent a return
110

sliding movement and, consequently, no additional tooth picks will be forced onto the arms 14.

It will be noted that as the tooth pick is removed the various moving parts are swung upwardly at the upper portion and then allowed to drop down by gravity. This causes the bar 21 and also the abutment 5 to move upwardly and downwardly, thus agitating the tooth picks carried by the support and also carried by the bottom 4. This agitation loosens the tooth picks so that they will not adhere and cause the tooth picks to rest against the vending wedge or member 12 as shown in Figure 1. When this member is lowered the notched members 11 will catch one or more tooth picks and then upon the return movement of the ejecting wedge 12 one tooth pick is vended and the remaining tooth picks forced back on to support 9. This action is carried out each time a tooth pick is vended.

In Figure 1 only a comparatively few tooth picks have been shown but, if desired, the entire chamber 2 could be filled and the parts would function as just described. When it is desired to fill chamber 2 the cover 25, which has an annular slip extension 26, is removed and the tooth picks inserted. The extension 26 is then slipped over the casing 1, and the parts are ready for further operation.

If desired a guiding post 27 could be connected to each of the arms 14 as shown in Figure 3, said guiding posts acting to cause the withdrawal of the tooth pick in such a manner that it will strike both of these posts substantially simultaneously and, therefore, not have either end wedged beneath the plate 15.

I claim—

1. A tooth pick vending machine comprising a casing having a chamber for receiving a supply of tooth picks, said chamber having an inclined bottom whereby tooth picks are adapted to gravitate toward a certain point, a shield for normally preventing the tooth picks from moving off said bottom, a support adapted to receive the tooth picks when permitted to move off said bottom, a swinging member carrying said support, a forked member adapted to receive a quantity of tooth picks from said support when the support swings to a given position, means carried by said swinging member for ejecting one of the tooth picks in said forked member, and a swinging member positioned to be swung against said forked member by the tooth pick being ejected for preventing a second ejection until the first mentioned tooth pick has been completely removed from the device.

2. A tooth pick vending machine including a forked member, means for directing tooth picks to said forked member, a pair of swinging arms,

said arms being connected together at one point, an ejecting wedge carried by said arms at the point where they are connected together, said ejecting wedge being positioned so that when said arms swing to one extreme position they will engage and force a tooth pick from said forked member onto the upper surface of said arms, a plate rigidly secured to said arms and arranged substantially parallel therewith, a pair of swinging and sliding plates pivotally mounted on said arms and formed with inclined upper surfaces normally extending across said plate at an angle whereby a tooth pick deposited on said arms will gravitate downwardly until it approaches the juncture of said sliding plates and the first mentioned plate, each of said sliding plates having a shoulder at one end and a pin coacting with said shoulder for preventing the sliding plates from moving in one direction while the tooth pick is engaging the upper surface of the opposite end of the respective sliding plates.

3. A tooth pick vending machine comprising a tiltable vending structure, and means for preventing the tiltable structure from functioning while a tooth pick is positioned near the discharge end of the vending structure, said means including a pair of pivotally mounted and sliding plates, each of said plates having at the inner end a shoulder and an extension at the lower end of each shoulder, and means forming an abutment for the shoulders positioned to engage the shoulders as said vending structure begins to function, said shoulders and abutment acting to prevent return movement of the vending structure until the vending operation has been completed.

4. In a tooth pick vending machine, a pivotally mounted vending structure including an arm over which the tooth picks are adapted to be moved when being vended, and a plate spaced from said arm but substantially parallel thereto, and means for preventing a second functioning of said vending structure until the first vending operation has been completed, said means including a pair of plates pivotally mounted on said arms and swingable therewith, the swinging of said arms causing said plates to have a slight reciprocatory movement, each of said plates having a shoulder and an extension adjacent said shoulder, and a stationary stop coacting with said extension on said shoulder, said extension acting on said stop to prevent swinging movement of the respective plates, and said shoulders acting to prevent sliding movement thereof when the vending structure has partially completed the vending operation.
